EDGAR L. BAILEY, OF DETROIT, MICHIGAN

MEANS FOR HEATING A CONDUCTIVE BODY

Application filed March 3, 1930. Serial No. 432,787.

This invention relates to an improved method and means for heating bodies, particularly conductive bodies.

Heretofore in heating apparatus of the type in which a body heated is employed as a core for collecting magnetic flux, a high voltage oscillating circuit of high frequency has been used with the result that operation of the apparatus involved danger and serious hazard to workmen coming in proximity thereto. With the prior devices, the portions of the body which are unfavorably located in the path of the flux do not develop as high temperatures as the other parts of the body, and when uniform heating is desired such apparatus is unsatisfactory for this reason.

The main objects of this invention are to provide improved means for heating bodies by electric induction; to provide means of this kind in which a non-oscillating circuit of substantially low frequency may be employed for obviating the danger of a high frequency oscillating circuit; to provide an improved heating device in which bodies of regular and irregular shapes may be heated uniformly with equal security.

Further objects of this invention are to provide inductive heating apparatus through which bodies may be progressively moved without interrupting the apparatus; to provide improved means in heating apparatus of this kind for heating the ends and other portions of bodies which are not advantageously located with respect to the main inductive flux of the apparatus, which may also be used to concentrate the effect of a local flux upon selected parts of a body; and to provide means of this kind which do not require electrical connections with the stationary parts of the apparatus, thereby permitting relative movement of the selectable heating means and the main flux producing mechanism during operation.

An illustrative embodiment of my invention is shown in the accompanying drawings, in which:

Fig. 1 is a view in side elevation of my improved heating apparatus showing a diagrammatic illustration of a power circuit.

Fig. 2 is a view in left end elevation of the heating apparatus shown in Fig. 1.

Fig. 3 is a view in vertical section taken on the line 3-3 of Fig. 2, looking in the direction indicated by the arrows.

Fig. 4 is a fragmentary horizontal sectional view of a collector coil and heating unit taken on the line 4-4 of Fig. 2, looking in the direction indicated by the arrows.

Fig. 5 is a view in side elevation of a heating apparatus embodying a modified form of my invention.

Fig. 6 is a view in end elevation of the apparatus shown in Fig. 5.

Fig. 7 is an enlarged sectional view taken on the line 7-7 of Fig. 5, showing a well known construction of insulated duplex wire.

In the form shown in Figs. 1, 2, 3 and 4, the heating apparatus includes a coil 1 having substantially twenty turns, each consisting of two No. 1 B.S. gauge wires 2 which are connected in parallel with the terminals 3 and 4 of a generator 5. The wires 2 are wound helically upon a frame which comprises upper and lower pairs 6 and 7, respectively, of longitudinal ribs in which notches 8 are formed for receiving the wires 2 and retaining the convolutions of the coil in spaced relation.

The upper pair of ribs or bars 6 are suspended from an overhead structure (not shown) by depending bracket arms 9, and the lower pair of ribs 7 rests upon a metal plate 10 which may be supported upon a floor or other suitable structure. Mounted on the pair of ribs 6, externally of the coil 1 is a metal plate 11. The plates 10 and 11, preferably comprise iron or other suitable metal, which is adapted to provide a path for the magnetic flux of the coil.

Extending longitudinally through the interior of the coil 1 at the bottom portion thereof, is a pair of rails 12 for supporting the wheels 13 of a carriage 14. The carriage 14 has a substantially flat platform 15 for receiving a metal body and conveying the same through the interior of the coil 1.

A collector coil 16, comprising a frame 17 on which substantially twenty turns of No. 6 wire 18 are wound, is mounted on the left end of the platform 15, as viewed in Fig. 1. This coil is located in a plane substantially normal to the longitudinal axis of the coil 1. The terminal portions 19 and 20 of the coil 16 are electrically connected to a pancake coil 21, which is suspended substantially within the collector coil and located at the central portion thereof, as viewed in Fig. 4. There are substantially ten turns of No. 6 wire in the pancake coil 21.

Electrically connected by conductors 22 and 23, in parallel with the pancake coil 21, is a second pancake coil 24, which is mounted on a support 25, secured to the right end of the platform 15 as viewed in Fig. 1. The metal body 16' is located on the platform between the pancake coils 21 and 22 which, in the form shown, are slightly spaced from the ends of the body 16'.

In the form shown in Figs. 4 and 5 the solenoid 1', of substantially the same construction as the solenoid 1, described above, is mounted on a frame having notched longitudinal upper ribs 6', and lower ribs 7'. Mounted on the upper and lower ribs 6' and 7' respectively, are metal plates 11' and 10', for concentrating the magnetic field of the coil, which is created by the current from a generator 5' that is electrically connected 40 with the terminal portions of the coil 1' by conductors 26 and 27.

A laminated metal core 28 preferably formed of superimposed plates of iron is located at the upper central portion of the interior of the coil 1'. This core is suspended from the upper plate 11' by U shaped members 29 and 30. Resting upon the end portion of the core 28, are coils 31 and 32, each having substantially twenty turns of 50 wire. Pancake coils 33 and 34 are detachably connected by couplings 35 and 36, to the coil 31 and 32 on the core 28 respectively.

Rails 12' are provided in the lower portion of the coil 1' for supporting wheels 13' of 55 a carriage 14', on which a metal body 37 may be positioned in the interior of the coil 1' and between the coils 33 and 34.

In operation, a low voltage, non-oscillating circuit having a substantially low frequency is supplied to the solenoid coils 1 and 1' in each form of my invention. Satisfactory results have been obtained by using 60 200 volts, at 180 cycles, giving a current of 360 amperes. This current sets up a magnetic field within the coil, which is induced

into the metal body therein, setting up hysteresis and eddy currents which develop heat in the metal of the body. The sides, top and bottom of the body are more advantageously located with respect to the flux of the coil 70 than the ends thereof, and as a result these portions are heated directly by the main flux of the coil to a greater degree than the ends.

With the form of my invention shown in Figs. 1 to 4 inclusive, a current is induced 75 in the collector coil 16 which is fed to the pancake coils 21 and 24. These coils cause the ends of the body to heat so that all portions thereof are substantially the same temperature. If it is desired, the coils 21 and 24 may be placed in close proximity to any selected portion of the body so as to concentrate the effect of the flux of the coil on such selected portion.

With the form of my invention shown in Figs. 5 and 6, the magnetic flux of the core 28 induces currents into the coils 31 and 32 on the respectively opposite ends thereof. The induced currents in the coils 31 and 32 are fed to the pancake coils 33 and 34 respectively, which are located in close proximity 80 to the end of the body 37.

In this manner, the sides of the body 37 are heated by the main flux of the solenoid, and the ends of the body are heated by the flux of the coils 33 and 34. The pancake coils 33 and 34 may be disconnected from their respective current feeding coils 31 and 32 by separating the couplings 35 and 36 so as to permit the carriage 14' to be moved 100 into the interior of the solenoid 1'.

Both forms of the above heating apparatus are particularly adapted for heating automobile bodies, refrigerator casings, etc., so as to dry or bake enamel thereon, but it has many diversified uses. With the apparatus shown in Figs. 1 to 4 inclusive it is possible to progressively convey bodies through the solenoid 1 by employing several trucks. By the term "enamel" as herein used in the specification and claims, is meant any and all suitable materials such as paint, varnish or other similar coating used to finish the surface of a metal body.

Although but two specific embodiments of this invention have been herein shown and described, it will be understood that numerous details of the construction shown may be altered or omitted without departing from the spirit of this invention, as defined by the following claims.

I claim:

1. In heating apparatus, an electric circuit, an outer coil electrically connected in said circuit for receiving conductive bodies and inducing heat generating current therein, a collector coil in proximity of said outer coil, and means electrically connected with said collector coil for augmenting the effect of said outer coil on selected parts of said body. 100

2. In heating apparatus, a coil, a support in said coil for retaining metal bodies in a substantially central position therein so as to use said bodies as a magnetic core for said coil, an electric circuit connected with said coil for inducing heat generating currents in the sides of said bodies, and means inductively energized by the flux of said coil for heating the ends of said bodies. 70
3. In heating apparatus, a coil, a support in said coil for retaining metal bodies in a substantially central position therein so as to use said bodies as a magnetic core for said coil, an electric circuit connected with said coil for inducing heat generating currents in the sides of said bodies, a collector coil in said first mentioned coil, and a pair of flux creating units electrically connected with said collector coil, one located at each end of said body. 75
4. In heating apparatus, a coil, a support in said coil for retaining metal bodies in a substantially central position therein so as to use said bodies as a magnetic core for said coil, an electric circuit connected with said coil for inducing heat generating currents in the sides of said bodies, means for collecting some of the flux generated by said coil, and a pair of auxiliary units adapted to be energized by the energy collected by said means for heating the ends of said body. 80
5. In heating apparatus, an electric circuit including a coil adapted to receive a conductive body for inducing heat generating currents therein, means externally located with respect to said coil for concentrating the magnetic flux thereof, said body serving as an internal core and having its sides exposed to the main flux thereof, and means inductively energized by the flux of said coil for heating the ends of said body. 85
6. Heating apparatus comprising a solenoid coil, an electric circuit for energizing said coil to produce a magnetic field therein, supports extending longitudinally through said coil, a carriage shiftably mounted on said supports for transferring a body through said magnetic field so as to induce heat generating currents in the sides thereof, and means mounted on said carriage at one end of said body and inductively energized by said magnetic flux for heating said end. 90
7. Heating apparatus comprising a solenoid coil, an electric circuit for energizing said coil to produce a magnetic field therein, supports extending longitudinally through said coil, a carriage shiftably mounted on said supports for transferring a body through said magnetic field so as to induce heat generating currents in the sides thereof, a collector coil on said carriage in the path of the flux of said field, and an auxiliary flux generating unit electrically connected with said collector coil for concentrating the effect of said flux on a selected portion of said body. 95
